DISPLAY RACK

Ernest R. Erickson, Des Moines, Iowa, assignor to
 C. E. Erickson Company, Incorporated, Des
 Moines, Iowa, a corporation of Iowa

Application September 8, 1936, Serial No. 99,782

7 Claims. (Cl. 211—148)

The object of my invention is to provide a display rack for displaying bread or other merchandise.

It has recently become the custom to display bread on racks in retail establishments and my rack is especially designed for that purpose, but my rack and many of its features could be used for displaying other merchandise.

It is my purpose to provide such a rack, which is very sturdy construction and at the same time very simple and economical to manufacture.

To this end, it is my purpose to provide a number of features of structure which will be hereinafter explained and claimed in detail, whereby a series of shelves may be assembled and rigidly connected together to form a rack with what appears to be two simple upright members spaced lengthwise of the rack for supporting the various shelves.

With these and other objects in view, my invention consists in the construction, arrangement and combination of the various parts of my display rack, whereby the objects contemplated are attained, as hereinafter more fully set forth, pointed out in my claims, and illustrated in the accompanying drawings, in which:

Figure 1 is a top or plan view of a display rack embodying my invention.

Figure 2 is a front elevation of the same.

Figure 3 is an end elevation of the rack.

Figure 4 is a detail, sectional view taken on the line 4—4 of Figure 1, illustrating the joint in the surrounding wall of the middle shelf.

Figure 5 is a detail, sectional view taken on the line 5—5 of Figure 4.

Figure 6 is a vertical, sectional view taken on the line 6—6 of Figure 2 and illustrating a supporting means for the shelves at one end of the rack.

Figure 7 is a detail, sectional view taken on the line 7—7 of Figure 6.

Figure 8 is a detail, sectional view taken on the line 8—8 of Figure 7.

Figure 9 is a perspective view of one end of the upright tubular supporting member, which is interposed between the lower shelf and the supports which stand on the floor.

Figure 10 is a detail, sectional view of the tube seat used in assembling my rack; and

Figure 11 is a similar view of another form of tube seat or washer.

Racks for the display of bread and of some other merchandise are largely purchased by the manufacturers and distributed to retailers gratis, being given to the retailers or more frequently

loaned to the retailer for use in displaying the manufacturer's bread.

On account of this method of distribution, according to which the manufacturer buys the racks and does not get any direct revenue from them, it is necessary that the cost to the manufacturer should be kept down, and therefore that the cost of manufacture should be as economical as possible.

Because such racks stand in a prominent position in the retailer's store, and because they affect the impression of the manufacturer's product, it is important that the racks should embody such structure as makes a favorable impression on the eye. Such a rack must be a good looking piece of store furniture.

My rack has been made with a view of complying with these requirements.

I will first describe the structure beginning at the bottom of the rack. It should be kept in mind that this mode of treatment of the rack does not necessarily indicate the order in which the parts are assembled.

Each rack has two members that I may call supports 10, comprising tubular members bent from a central point downwardly toward each end, and provided at their ends with smooth caps 11, which rest on the floor.

At the middle of each support 10 resting thereon is a metal saddle 12, which has substantially the form of a downwardly opening rectangular box. The side walls of the saddle 12 straddle the support 10 and rest thereon as indicated at 12a in Figure 7.

The end walls of the saddle 12 have their lower edges shaped to fit the top of the support 10 as indicated at 12b in Figure 7.

At the middle of the upper part of the saddle 12 is an annular raised portion 12c, which has a radially projecting lug 13.

A tubular member 14 comprising a piece of pipe has in its ends, notches 15. One end of the tubular member 14 rests on the saddle 12 and snugly receives the raised annular portion 12c with the lug 13 projecting into one of the notches 15.

At 16, I have indicated the lower shelf of the rack.

Fastened to the under side of the shelf 16 in the manner hereinafter more fully explained is a metal washer 17, which has a central, annular downstruck part 18, provided with a lug 19, like the lug 13 already described.

The upper end of the tubular member 14 receives the down-struck portion 18 of the washer 17.

17 with the lug 19 received in a notch 15 in the member 14.

Resting on top of the shelf 16 above each of the washers 17 is a tube or pipe seat 20, which I will now more particularly describe. Either the washer tube seat 17 or the tube seat 20 may be used, as may be desired.

This tube or pipe seat 20 is made from an annular metal disc, which is shaped in a press or the like to form a central cup-like depression 21, with an annular, external inclined flange 22.

The parts are so arranged, for example, that when what I call the under side of the periphery of the tube seat 20 rests against a flat surface, the under side of the cup 21 will be held slightly away from such surface.

One of these tube seats 20 is fastened to the upper side of the shelf 16 by means of bolts 23, which extend through the holes 24 in the flange 22 near the cup-shaped depression 21 and then through the shelf 16 and through suitable holes in the washer 17. These bolts have nuts 25. By drawing the nuts tightly on the bolts, the under side of the cup-shaped portion 21 may be drawn tightly against the shelf.

Received in the cup-shaped portion 21 of the tube seat 20 is the lower end of an upright, tubular member 26.

At the upper end of the tubular support 26 is a second shelf 27, which is a little shorter and a little narrower than the shelf 16.

Interposed between the tubular member 26 and the shelf 27 is another of these tube seats 20 turned upsidedown.

On top of the shelf 27 is another tube seat 20, which may be slightly smaller than the ones used in connection with the tube 26. It is smaller because the upper tubular supporting member 28 is slightly smaller than the member 26, which likewise is slightly smaller than the member 14.

By smaller I mean of less outside diameter.

At the upper end of the tubular member 28 is a top shelf 29 on the under side of which is another tube seat 20 like that at the lower end of the tube 28.

This upper tube seat 20 is fastened to the shelf 29 by bolts 30 and nuts 31.

Each of the tube seats has a central hole 32.

The raised portion 12c of the saddle 12 has a central hole 33.

In the under side of the shelf 29 is a recess 34 to receive the head of a long tie bolt 35, which extends through all of the tube seats 20 and through the saddle 12 and through the support 10, and has on its lower end a lock washer 26 and a nut 37.

It will be seen from the foregoing that I have provided a structure having parts which lend themselves to ready and convenient assembly into a rigid display rack.

It will be noted that on account of the fact that the washer 17 is fastened by the bolts 23 to the shelf 16 and the further fact that the washer 17 and saddle 12 are provided with the lugs 13-19, which cooperate with the notches 15 at the ends of the tubular member 14, and the further fact that the saddle 12 has its ends shaped to partially encircle the support 10 as shown in Figure 7, the support 10 cannot twist or rotate on the vertical axis, but will always remain in the relative position it assumes when the parts are assembled.

On account of the arrangement here shown, it will also be noted that no bolts are needed for fastening the tube seats 20 to the shelf 27.

It may be mentioned that when the nut 37 is tightened, the members 20 above and below the shelf 27 will be pressed tightly against the shelf.

The shelves 16, 27 and 29 are preferably wood, although they might be made of metal.

In the form which I prefer the middle shelf 27 has a peripheral wall 38. The wall 38 has a structure which lends itself to cheap and rapid manufacture and assembly.

The wall 38 is made in four sections which have joints at the ends of the shelf midway from the sides thereof and at the sides of the shelf midway between the ends thereof. Thus each section is in the form of an angle which extends around one corner of the shelf. As shown in Figure 1, a section of the wall 38 is indicated at 38a. At the end of each section, the edge thereof is provided with a series of tongues 39 and recesses or grooves 40. The adjoining section has coacting tongues 39 and grooves 40. The grooves 20 are wider at their bottoms and the tongues are correspondingly shaped, so that the adjacent ends of two sections can be locked together as best seen in Figure 4.

To further strengthen the wall 38, I provide a metal clip 41, which is simply an upright strip having its upper ends bent inwardly and then downwardly as at 41a to receive the upper edge of the wall 38 at one of the joints.

The main portion of the clip 41 is on the outside of the wall and covers the joint and is fastened to the shelf 27 by means of a screw 42 extending through the clip 41, the wall 38 and into the shelf 27. (See Figure 5.)

The shelf 29 is narrower than the shelf 27 and is just enough shorter to snugly fit between the ends of the wall 38 for storage and transportation.

As shown in Figure 1, the shelf 29 can be set on the shelf 27 and will fit within the wall 38.

A device of this kind can be conveniently stored and transported in knock-down form.

It will, of course, be understood that all the holes are bored or drilled in the parts, so that the parts may be conveniently and readily assembled into the completed rack.

There is another advantage in arranging the joints in the middles of the sides and ends of the wall 38. By so doing, the corners of the shelf 27 can be cut off, leaving openings between the shelf 27 and the wall 38 as indicated at 50 in Figure 1. Through these openings, crumbs or the like may be discharged for conveniently cleaning the shelf 27, which has the wall 38.

It will be obvious from the foregoing description that changes may be made in the construction and arrangement of the parts of my improved display rack, and it is my purpose to cover by my claims any modifications which may be reasonably included within their scope and the scope of my invention.

I claim as my invention:

1. A display rack having at each end a support, comprising a tube curved from its central part downwardly to its ends and provided with a cap on its ends, a saddle fitted on the top of the support having an upstruck portion to be received within the end of a tubular member, said portion having a laterally projecting lug, a tubular member having a notch in its wall, at each end, said tubular member resting on the saddle with said lug received in the lower one of said notches, a washer with a down-struck central portion received within the upper end of said tubular member and provided with a lug projecting into the

notch in the upper end of the tubular member, said rack having a shelf having at each end means extending lengthwise through the shelf, the washer, the tubular member, saddle and the tube for binding the parts together.

2. A display rack having at each end a supporting means and a saddle resting thereon, having a central upstruck portion and a tube on the saddle receiving said upstruck portion, and a washer at the upper end of the tube having a down-struck portion projecting into the tube, a shelf secured to said washer, said tubes and said saddles and washers having coacting parts to prevent relative rotation thereof, the saddles and the supports having coacting parts to prevent relative rotation thereof.

3. A display rack having spaced supports and a plurality of vertically spaced shelves, means for supporting the shelves on the supports and in spaced relation to each other, said means comprising a single upright at each end of the rack, comprised of vertical tubular sections between the respective shelves and a tie rod extending from the top shelf through the vertical sections to the support, the supporting means of each end of the rack having projecting parts to prevent the rotation of the supports with relation to the shelves.

4. A display rack having at each end a support, comprising a member curved from the central part downwardly and laterally to its ends, and a saddle fitted on top of the support having portions to straddle the support and having an upstruck portion formed with a laterally projecting lug, a tubular member, said upstruck portion being adapted to fit in an end thereof, said tubular member having a notch in its wall at each end, said tubular member resting on the saddle and receiving the upstruck portion thereof and receiving said lug in one of said notches, a washer with a downstruck central portion snugly fitted

within the upper end of said tubular member and provided with a lug projecting into the notch in the upper end of the tubular member, a shelf secured to the upper parts of said washers, and a tie rod rigidly fastening together the members of each support.

5. A display rack having a plurality of shelves and having at each end a support comprising a member curved from its central portion downwardly to its ends, a saddle seated non-rotatably on top of the support, tubular elements interposed between the saddle and the lowermost shelf and between each successive pair of shelves, metal members secured to the shelves to receive the upper ends of said tubular members, rods anchored to the topmost of said metal members and extending downwardly at each end of the rack through the successive shelves and tubular members and secured to the supports.

6. A display rack having at each end a support comprising a tube curved from its central part downwardly to its ends and provided with a cap on its ends, a saddle fitted on the top of said tube, said rack having a shelf provided at each end with means extending through the shelf, the saddle and the support for binding the parts together.

7. A display rack having spaced supports and a plurality of vertically spaced shelves, means for supporting the shelves on the supports and in spaced relation to each other, said means comprising a single upright at each end of the rack formed of vertical tubular sections between the respective shelves and saddle members between the lower shelf and said supports, and a tie rod extending from the top shelf through the vertical sections to the support, said saddle members engaging said supports to prevent the rotation of the supports with relation to the shelves.

ERNEST R. ERICKSON. 40
